US00D861656S

(12) **United States Design Patent** (10) **Patent No.:** **US D861,656 S**
(45) **Date of Patent:** **** Oct. 1, 2019**

(54) **CASE FOR ELECTRONIC COMMUNICATIONS DEVICE**

(71) Applicant: **SPIGEN KOREA CO., LTD.**, Seoul (KR)

(72) Inventor: **Sun Woo Yun**, Seoul (KR)

(73) Assignee: **SPIGEN KOREA CO., LTD.**, Seoul (KR)

(**) Term: **15 Years**

(21) Appl. No.: **29/586,045**

(22) Filed: **Nov. 30, 2016**

Related U.S. Application Data

(63) Continuation of application No. 29/585,493, filed on Nov. 23, 2016, now Pat. No. Des. 836,621.

(51) **LOC (12) Cl.** **14-03**

(57) **CLAIM**

The ornamental design for a case for electronic communications device, as shown and described.

DESCRIPTION

FIG. 1 is a front perspective view of a case for electronic communications device showing my new design in an environment of use;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front perspective view of the case for electronic communications device shown exploded from environmental subject matter;

FIG. 10 is a rear perspective view of the case for electronic communications device shown exploded from environmental subject matter;

FIG. 11 is a front perspective view of the case for electronic communications device shown without environmental subject matter; and,

FIG. 12 is a rear perspective view of the case for electronic communications device shown without environmental subject matter.

The broken lines depict environmental subject matter and portions of the case for electronic communications device that form no part of the claimed design. The broken lines and regions bounded by broken lines form no part of the claimed design.

1 Claim, 12 Drawing Sheets
